UNITED STATES PATENT OFFICE

PETER H. WELTER, OF KANSAS CITY, KANSAS

CAR-DOOR HANGER

Application filed October 23, 1929. Serial No. 401,768.

The object of this invention is to provide a device whereby one man may readily and safely hang a car door, thereby doing the work of a number of men heretofore required for carrying out the same operation by hand,—there always being the possibility of injury to one or more of the individuals engaged owing to the danger of the door falling before being properly hung.

10 A further object is to provide a device adapted for hanging car doors and for other similar purposes, which shall include a cradle or hoisting device receiving the door, a relatively stationary structure and means for supporting that structure with reference to a pair of ground wheels and an axle, whereby the correct position may be secured after the operator has first brought the cradle mounting and lifting means, that is the 15 main structure, to the approximate position required for effecting the hanging of the door.

20 A further object is to provide lifting means adapted to automatically retain the elevation which has been secured, thru the use of worm gearing, and other lifting and lowering means adapted for use when desired.

25 With the foregoing and other objects in view, the invention consists in the novel construction and arrangement of elements disclosed, it being understood that modifications may be made within the scope of the claims without departing from the spirit of the invention.

30 In the drawings forming part of this application:—

35 Figure 1 is a view of the device in vertical longitudinal section, the section being on line 1—1 of Figure 2, and showing many of the elements in elevation.

Figure 2 is a top plan view.

40 Figure 3 is a section on line 3—3 of Figure 1.

45 Figure 4 is a view showing a fragmentary portion of a car, and showing in vertical transverse section the apparatus designed to receive and place the car door in position with reference to the track on which it is to 50 be hung.

A main structure includes a platform 10, and a drop axle 11, with reference to which the platform is slidable, the bar 12 being apertured at 13 and extending across the platform and engaging at said point 13 the deflected portions of the axle. The movement of the platform longitudinally of the axle, will be apparent from an inspection of Figure 2, considered in connection with Figures 3 and 4. The ground wheels are 60 designated 15 and 16 and the structure which is sometimes termed a cart, is controlled by means of a handle or bail member 18 mounted as shown in Figures 1 and 2 and supported in part by brace or braces 65 19. (Boxes 20 receive the axle.)

A plurality of vertically extending elements such as 21 and elements 22 spaced therefrom and adapted to cooperate in the formation of vertical guides are designed to 70 receive and permit of the vertical movement of the cradle or carrier which will place the door in the position desired. In Figure 1 upper corner members or plates are designated 24 and 25 and lower corner plates are 75 shown at 26 and 27, all of these corner elements being mounted in a fixed position and properly secured as illustrated, and being connected by diagonal braces such as 28 and 29. The braces in turn may be secured together at the point 30.

The door cradle, or carrier includes the upper horizontal member 32, the lower horizontal member 33, and the vertical members 34 and 35 with which said horizontal 85 members are connected. The trough-like element 36 receives the lower edge portion of the door and is secured to the cradle, and the upper edge of the door 37 is retained by means of a clip or pivoted bracket 38, the 90 pivotal member being designated 32, and the device being controlled by means of chain 40 adapted to be secured within the notched upper end portion of the bracket 42 mounted on the base 10 of the main 95 structure.

A hoisting cable 45 is connected at one end, considered as the dead end, at the point designated 46 on the relatively stationary structure. This cable passes around lower 100

pulley 47, thence around another lower pulley 48, and around upper pulley 49. Pulleys 47 and 48 are mounted on the cradle or carrier and pulley 49 is mounted on the stationary structure.

The hoisting device includes a shaft 50, carrying a hand wheel 51 and mounting a worm 52 meshing with worm wheel 53 on shaft 54 of the drum or windlass 55. This 10 provides a form of cable winding device by means of which the cradle or carrier may be elevated and caused to maintain an adjusted position.

If desired, the winding device shown at 15 the right of Figure 2 may be employed, and the cable not only passes around drum 55, but around drum 56 on shaft 57, the latter carrying a hand wheel 58. This drum 56 has associated therewith a conventional 20 pawl and ratchet mechanism, shown at 59 and 60, the element 60 being the ratchet wheel.

What is claimed is:—

1. A car door hanger comprising a portable platform, a supporting structure on the platform, a frame slidable in the supporting structure, a door supporting member on said frame to engage the lower edge of a car door and permit the door to be 25 tilted relative to the frame, pivoted manually controlled means to engage the upper edge of the door and carried by the frame and cooperating with the door supporting member in holding the door against relative 30 movement with respect to the frame and when actuated frees the door for tilting movement on the supporting member for permitting the door to be positioned for an engagement with the door supporting means 35 of a car, and means to raise and lower the frame.

2. A car door holder comprising a portable platform, pairs of vertical side members carried by the platform, side members 45 slidable in the pairs of vertical guide members, a channel door supporting member connecting the side members and engaging under the door edge of a car door, a rod journaled to the side members, a clip secured 50 to the rod and engaging over the upper edge of the car door, a manually operating means connected to the clip to disengage the latter from the door to permit tilting of the door on the door supporting member, and means 55 to raise and lower the side members.

In testimony whereof I affix my signature.
PETER H. WELTER.
